Letters Patent No. 2107 Dated July 14, 1865.

Design for a Soldier's Memorial.

The schedule or record to in these Letters Patent and making part of the same.

To all whom it may concern:

Be it known that of John C. Andrews of Woodstock, in the County of Oxford, and State of Maine have invented a new and Original design for a Soldier's Memorial: and I do hereby declare that the following is a full, clear and exact description thereof, which will enable others skilled in the art to make and use the same, reference being had to the accompanying drawing forming part of this application

My invention consists in ornamenting a metallic or other plate to be set in a suitable frame by engraving thereon a design consisting of an American eagle standing upon the Union Breast-plate, and holding in his beak the American flag, and surrounding, or nearly surrounding, the same with a branch of laurel on the one side, and a branch of oak on the other, with their stems crossed underneath the breast-plate. The said plate having sufficient space left for inserting under an opening or hole in the same the likeness of the soldier or person whose military or naval career it is intended to commemorate, and also for engraving round about the same his name, and all the particulars of his military or naval career.

The Figure in the accompanying drawing represents my new design for a Soldier's Memorial incorporated within a suitable frame.

A is the plate which, and B, the frame in which it is set. On the upper part of the plate there is engraved an American eagle C, with his wings partially expanded, his feet standing upon the union breast plate D, which is represented as partially resting upon a branch of laurel a, and of oak b, at the part where they cross each other E is an American flag floating from a staff, which the eagle holds aloft in his beak.

This design of the eagle and breast plate and flag is surrounded, or nearly surrounded by a branch of laurel a, denoting victory and beauty, on the one side, and by a branch of oak b, denoting strength and majesty on the other.

Underneath the design, there is made a circular opening for exhibiting the likeness of the soldier or officer for whom the memorial is intended, which likeness is placed on the back of the plate, so that the face will show through the opening therein.

Around this likeness there is to be engraved the name of the soldier or officer, the Company, Regiment, Division, Army Corps, in which he served, or which he commanded, as well as all other particulars in his military career, such as the battles in which he was engaged, and the date &c. &c. thereof. I do not wish to be understood as claiming either the opening for the display of the soldier's likeness, or such inscription as may be engraved on the metallic plate, as forming a part

3 of the design

What I claim as new and desire to secure by Letters Patent is The within described new and ornamental design for a soldier's memorial, substantially as specified.
